APPLICATOR TOOL FOR ELECTRICAL
PASS-THROUGHSJan de Swart, Los Angeles, Calif., assignor to
Shellmar Products Corporation, Mount Vernon,
Ohio, a corporation of Delaware

Application March 23, 1946, Serial No. 656,591

1 Claim. (Cl. 218—19)

1

My invention is concerned with a hand tool or applicator for installing an electrical connecting device or pass-through.

In the production and installation of certain types of electrical equipment it is frequently necessary to connect a wire which is located on an accessible side of a partition with another wire which is located on the opposite or inaccessible side of the partition. This connection may be made by drilling, or otherwise providing, a hole in the partition, drawing the inaccessible wire through the hole and securing it by soldering, or the like, to a connecting device or pass-through, installing the pass-through in the hole and then securing the wire on the accessible side of the partition to the pass-through.

It is an object of my invention to provide an applicator or hand tool, which is particularly designed for installing in an aperture in a partition, an electrical connecting device or pass-through of the type which comprises an outer securing sleeve and a telescoping insulator covered core member wherein the sleeve is provided at one end with an outwardly directed abutment portion and at the other end with inwardly directed expandable portions which initially engage in a recess in the insulator portion of the core member whereby when the connecting device is positioned in the aperture with the abutment portion in engagement with one side of the partition and the core member is pulled toward said abutment the expandable portions of the sleeve will buckle outwardly and form a securing shoulder in engagement with the other side of the partition.

It is an object of my invention to provide a hand tool having an inner member provided with resilient jaws, an outer telescoping member provided with resilient abutment members and an operating mechanism to move the jaws into engagement with the abutment member to cause the jaws to grip an element placed between the same and move it in the direction of the abutment members.

These and other objects will be apparent from a description of my device which is illustrated by way of example in the accompanying drawings, wherein:

Fig. 1 is an elevation of my applicator tool with a portion of the operating handle broken away;

Fig. 2 is an end view of the device shown in Fig. 1;

Fig. 3 is a section on the line 3—3 of Fig. 1;

Fig. 4 is a section on the line 4—4 of Fig. 2;

Fig. 5 is an elevation showing the connecting device or pass-through which my applicator is particularly designed to install;

Fig. 6 is a view partly in section showing the connecting device in position in an aperture with my applicator in position to install the same; and

Fig. 7 is a view similar to Fig. 6 showing the

connecting device installed in the aperture but not yet released from the applicator tool.

My applicator tool, as illustrated in the drawings, is particularly designed to install in an apertured wall or partition an electrical connecting device or pass-through, of the type illustrated in Fig. 5, which comprises an outer securing sleeve 10 and an inner connecting element 11. The inner connecting element 11 includes a rod-like core member 12 around which a plastic insulator member 13 has been molded. The insulator member 13 is provided with a circumferential groove 14 which receives the inturned slotted end 15 of the securing sleeve 10. The securing sleeve 10 is provided at the other end with a circumferential outwardly extending flange or abutment shoulder 16.

My applicator tool comprises an inner rod-like tension applying member 20 and an outer tube-like section or body member 21. The inner member 20 is provided at one end with resilient jaw-like portions or members 22 separated by slots 23 which extend radially inwardly to a central recess 24. The slots 23 extend axially of the member 20 to permit movement of the jaw members 22 towards each other to engage in gripping relation an end 25 of the rod-like core 12 of the connector member 11 when it is positioned in the recess 23. Serrations 26 may be provided at the outer ends of the jaw members 22 to increase their gripping action. The outer surfaces 27 of the jaw members 22 are beveled in an inward axial direction. The inner member 20 extends into the outer tubular member 21 and is provided at its inner end with a pin 28 which extends outwardly through parallel guide slots 29 in the outer member 21.

The outer member 21 is provided at one end with resilient abutment portions or fingers 30 separated by spaced slots 31. The inner surfaces of the fingers 30 are shaped as shown in Fig. 4 to provide an inwardly tapered surface 32 for engagement with the tapered outer surfaces 27 of the jaw members 22 when the inner member 20 is moved into the outer tube 21 to bring these surfaces into engagement.

A handle member 33 is provided with downwardly directed legs 34 which are pivoted at 35 to the tube 21 adjacent its slotted end. The links 36 are connected at one end to the handle member 33 by pivot 37 and at the other end to the pin 28 extending from the inner member 20. By moving the gripping portion 38 of the handle 33 toward the tube 21 the pin 28, guided by slots 29, is moved inwardly of the tube 21, and the inner surfaces 32 of the fingers 30 are brought into engaging relation with the outer surfaces 27 of the jaw members 22.

I have illustrated the use of my applicator tool in Figs. 6 and 7. After the end of the wire 39

on the inaccessible side of the partition 40 is drawn through the aperture 41 and soldered or otherwise secured to the end 42 of the core member 12, the connecting device is positioned in the aperture 41 of the partition 40 with the flange 16 of securing sleeve 10 in engagement with the accessible surface of the partition 40 and end 25 of the core 12 extending outwardly of flange 16. My applicator tool is then positioned with the end 25 of core 12 extending into the recess 23 in the tension applying rod 20 and the ends 10 of the abutment fingers 30 in engagement with the flange 16. The gripping portion 38 of the applicator handle 33 is then moved toward the tube 21 and the surfaces 32 engage the surfaces 27 to force the jaws 22 into gripping relation with the end 25 of the core 12. Further movement of the gripping portion 38 toward the tube 21 moves the inner element 11 of the connecting device towards the flange 16 and causes the end portions 15 of the securing sleeve 10 to expand or buckle outwardly and form a shoulder 43 in engagement with the inaccessible surface of the partition 40. The split ends 30 of the tubular member 21 will expand under pressure from the jaws 22 and permit the jaws 22 to move into the tube 21 after they engage in gripping relation with the rod 25 a sufficient distance to bring about the clinching or expanding action of the end 15 of the member 10 as illustrated in Fig. 7. The tool may then be removed by moving the gripping portion 38 of the handle 33 away from the body member 21 to release the gripper jaws 22 from gripping relation with the end 25 of the core 12. The installation of the connecting device is then completed by securing to the core end 25 the end of the wire on the accessible side of the partition 40.

While I have described my applicator tool as embodying specific details of construction and as used in the installation of a specific device it will be understood that other details and other uses may be resorted to within the spirit of my invention.

I claim:

An applicator, for installing in an aperture in a panel, a two-part electrical pass-through device of the type having an outer flanged sleeve adapted to be positioned in the aperture with the flange in engagement with one side of the panel and an inner interengaging insulated connecting rod which is movable within the sleeve to cause one end of the sleeve to expand into engagement with the other side of the panel to secure the device in the panel, comprising a hollow tube having a slotted end adapted to be engaged with the flange on the securing sleeve of said pass-through, a tension applying rod telescoped in said tube, said tension applying rod being axially split at the end to provide gripper jaws normally extending exteriorly of said tube at the slotted end thereof, pin and slot guide means connecting said tube and said tension applying rod, and pivotally connected manually operated link members for moving said tension applying rod within said tube, the slotted end of said tube and said gripper jaws having cooperating engaging surfaces for contracting said gripper jaws into clamping engagement with said inner connecting rod of said pass-through and thereafter moving it in an axial direction in said securing sleeve.
